US0D1111165S

(12) **United States Design Patent** (10) **Patent No.:** **US D1,111,165 S**
(45) **Date of Patent:** **** Feb. 3, 2026**

(54) **FOETAL VACUUM EXTRACTOR HANDLE**

(71) Applicant: **Shore Medical Pty Ltd**, South Murwillumbah (AU)

(72) Inventor: **Philip Wharton**, South Murwillumbah (AU)

(73) Assignee: **SHORE MEDICAL PTY LTD**, South Murwillumbah (AU)

(**) Term: **15 Years**

(21) Appl. No.: **29/972,070**

(22) Filed: **Nov. 7, 2024**

(30) **Foreign Application Priority Data**

May 16, 2024 (AU) 202413057

(57) **CLAIM**

The ornamental design for a foetal vacuum extractor handle as shown and described.

DESCRIPTION

FIG. 1 is a front perspective view of a foetal vacuum extractor handle, showing my new design;
FIG. 2 is a left side elevation view thereof;
FIG. 3 is a right side elevation view thereof;
FIG. 4 is a top plan view thereof;
FIG. 5 is a bottom plan view thereof;
FIG. 6 is a front elevation view thereof; and,
FIG. 7 is a rear elevation view thereof.

1 Claim, 5 Drawing Sheets
